[57] **CLAIM**

The ornamental design for a pedestal housing for cable television components, substantially as shown and described.

DESCRIPTION

FIG. 1 is a front perspective view of a pedestal housing for cable television components showing our new design;

FIG. 2 is a rear elevational view thereof;

FIG. 3 is a bottom plan view thereof, and

FIG. 4 is a perspective view of a modified form of the pedestal housing for cable television components shown in FIG. 1.

The side of the housing not shown is a mirror image of the side shown.
